UNITED STATES PATENT OFFICE.

EDWARD RYAN AND OSCAR JOHNSON, OF CHICAGO, ILLINOIS.

LOCOMOTIVE-TENDER.

No. 904,017.

Specification of Letters Patent.

Patented Nov. 17, 1908.

Application filed December 9, 1907. Serial No. 405,728.

To all whom it may concern:

Be it known that we, EDWARD RYAN and OSCAR JOHNSON, citizens of the United States, residing at Chicago, county of Cook, and State of Illinois, have invented certain new and useful Improvements in Locomotive-Tenders, of which the following is a specification.

Our invention relates to locomotive tenders and the object of our invention is to provide a tender of such improved construction that the coal in the coal pit may be moved forwardly as required to the front end of the tender where it is more readily accessible.

15 A further object of our invention is to provide a tender of the character mentioned having a coal pit of large capacity.

Other objects will appear hereinafter.

With these objects in view our invention 20 consists generally in a tender comprising a water tank substantially co-extensive with the length and breadth thereof and having an inclined top portion near its forward end, in combination with a coal pit arranged 25 above said tank and comprising a movable inclined bottom, side and back walls rigidly fixed to said bottom and movable therewith, the front of the pit being defined by the angularly disposed walls of the front water 30 legs of the water tank rising from the front end of said tank, and in a fluid pressure device for operating the movable portion of the pit.

Our invention further consists in a tender 35 comprising a water tank as before mentioned, and a coal pit having a movable bottom, the forward portion of said bottom being angularly disposed or forwardly inclined and the rear portion being substantially horizontal when in normal position and overhanging the rear portion of the tank.

Our invention further consists in various 45 details of construction and arrangements of parts all as will be hereinafter fully described and particularly pointed out in the claims.

Our invention will be more readily understood by reference to the accompanying drawings forming a part of this specification and in which,

Figure 1 is a plan view of a tender embodying our invention in its preferred form, Fig. 2 is a vertical longitudinal section on the line $x-x$ of Fig. 1, Fig. 3 is a similar 55 view illustrating the movable bottom of the coal pit in raised position, Fig. 4 is a ver-

tical transverse section on the line $y-y$ of Fig. 2, and Fig. 5 is a detail.

Referring to the drawings, 1 indicates the water tank of the tender which extends the full length and width thereof and constitutes the body portion. The forward end, 2 of the tank is quite shallow, the top, 3 thereof forming the floor at the forward end of the tender. From the portion, 3, which extends a short way rearwardly forming the extreme forward end of the bottom of the coal pit, the top of the tank inclines upwardly as at 4 to the top plate, 5.

Rising from the forward end, 2 of the tank are the water legs, 6, having the inwardly and forwardly inclined walls 7 forming the front of the coal pit. The coal pit is arranged above the water tank and is the full width of the tender. The coal pit is defined by a movable bottom, 8, the sides, 9 rigidly fixed thereto and the back or rear wall, 10. The bottom comprises a forwardly inclined portion, 8', substantially co-extensive with the inclined portion, 4 of the top of the water tank, and a substantially horizontal portion, 8'' which extends rearwardly, overhanging the top, 5 of the tank. The lower forward edge of the bottom is hingedly connected to the tank at the junction between the portions, 3 and 4 of the top, 11 indicating the hinge. The bottom is preferably strengthened by a plurality of angles or T irons, 12 and the back is strengthened by a brace, 13 riveted thereto and to the portion 8'' of the bottom. The sides, 9 slightly overhang the sides of the tank in order that their forward ends will pass the outside walls of the water legs.

14 indicates a brace to prevent bulging of the forward ends of the wall, 9. This comprises an angle or T iron having the vertical portions, 15, which are riveted to the forward edges, and the transverse portion, 16 which extends above the water legs, 6, the upper ends or tops of the water legs being curved as at 17 to permit the portion, 16 of the brace to swing freely above it.

Within the tank, 1 is arranged a cylinder, 17 having a piston, 18 which is actuated by fluid pressure either steam or compressed air from the engine, and controlled either from the cab of the engine or the front of the tender or both. The cylinder, 17 is preferably of the same height as the rear portion of the tank and is provided with the top and base flanges, 19 and 20 respectively

which are riveted to the top and bottom plates of the tank. It is obvious that the cylinder thus constitutes a support or brace for the tank. The piston, 18, is connected by a pitman, 21, to the bottom of the coal pit, preferably to the portion, 8". By admitting fluid pressure to the cylinder as by the pipe 22, the coal pit may be raised as indicated in Fig. 3 causing the coal to move forwardly to the front of the tender where it is readily accessible.

To better aid in supporting the coal pit when raised the upper end of the pitman, 21 is formed T shaped, the horizontal portion, 23 extending transversely of the pit and having bearings 24 near the sides of the bottom, 8". The top of the cylinder is slightly enlarged and is provided with a plurality of grooves, 25, which permits the steam or compressed air to escape by the piston after the pit is raised to its full height. By this construction the piston is never forced out of the cylinder, the grooves 25 being proportioned to carry off all pressure admitted through the pipe, 22.

Having described our invention what we claim as new and desire to secure by Letters Patent is:

1. A locomotive tender comprising a water tank substantially co-extensive with the length and breadth thereof and having an inclined intermediate top portion in combination with a coal pit arranged above said tank and comprising a movable bottom, side and back walls rigidly fixed to said bottom and movable therewith and fluid pressure means for raising said pit as and for the purpose specified.

2. A locomotive tender comprising a water tank substantially co-extensive with the length and breadth thereof and having a pair of water legs rising from the forward end thereof, in combination with a coal pit comprising a movable bottom hingedly connected to the top of said tank to the rear of said water legs, sides fixed to said bottom and overhanging the sides of said tank and adapted to swing in a plane parallel with the outer faces of said water legs and fluid pressure means for raising said pit, substantially as described.

3. A locomotive tender comprising a water tank substantially co-extensive with the

length and breadth thereof and having a pair of water legs rising from its forward end in combination with a coal pit comprising a movable bottom hingedly connected to the top of said tank to the rear of said water legs, sides fixed to said bottom and having their forward ends extending on the outside of said water legs, a brace extending over said water legs and connecting the forward ends of said sides and fluid pressure means for raising said pit, substantially as described.

65

4. A locomotive tender comprising a water tank substantially co-extensive with the length and breadth thereof and having a forwardly inclined intermediate top portion, in combination with a coal pit arranged above said tank and comprising a bottom having an inclined portion substantially co-extensive with the inclined top portion of the tank and a substantially horizontal portion overhanging the upper rear portion of the tank and sides and a back fixed to said bottom and fluid pressure means for raising said pit substantially as described.

70

5. A locomotive tender comprising a water tank substantially co-extensive with the length and breadth thereof, in combination with a coal pit having a movable bottom hingedly arranged above said tank, a cylinder arranged within said tank and having a piston suitably connected to the bottom of said pit and means for supplying fluid pressure to said cylinder, substantially as described.

80

6. A locomotive tender comprising a water tank forming the body thereof in combination with a coal pit hingedly arranged above said tank, a cylinder arranged within said tank and extending from the top to the bottom thereof, a piston in said cylinder and suitably connected to said pit and means for supplying fluid pressure to said cylinder, substantially as described.

90

In testimony whereof we have signed our names to this specification in the presence of two subscribing witnesses.

EDWARD RYAN.
OSCAR JOHNSON.
